ELECTRICAL CABLE

Application filed August 18, 1930. Serial No. 475,094.

The object of this invention is to provide a cable in which the skin effect of large power cables is reduced to a minimum.

Skin effect is that well known phenomenon of alternating currents in which the internal induction in a conductor causes the current density to be a minimum at the center of the cross section of cable and a maximum at the periphery. If the conductor is a cable, that is, composed of a number of strands, then the skin effect consists in each of the outer strands carrying more current than each of the inner strands. The greater the distance of a strand from the center, the more current it carries. Considering all of the strands of a cable as so many equal conductors connected in multiple, it can be shown by elementary mathematics, that the energy lost in transmitting a given current I , through the cable, is a minimum when each strand carries the same quantity of current. If the total true resistance of the cable is called R , the total alternating current is called I , the true resistance of each strand, r , and the current in any strand is called i , being a variable, different in quantity for different strands, then the total heat generated and lost in the cable is $\Sigma i^2 r$; dividing this by I^2 gives a quotient which we will call R' , which is commonly called the apparent resistance of the cable due to skin effect at the frequency under consideration. If all strands carry equal currents, it is obvious that R' is equal to R . If all strands do not carry equal currents, that is, i is a variable, then $\Sigma i^2 r$ is not a minimum and R' is greater than R . The ratio R' over R is called the skin effect factor and is greater than unity.

In the drawings, Fig. 1 is a diagram of a preferred arrangement of cable strands;

Fig. 2 is a cross-sectional perspective view of a complete, sheathed, cable;

Fig. 3 is a similar view with the sheaths or coverings omitted;

Fig. 4 is a diagrammatic view showing one possible arrangement of the strands of the cable;

Fig. 5 is a view of the tubular arrangement of the strands shown in Fig. 4 flattened out;

Figs. 6, 7, 8, 9 and 10 are diagrams of possi-

ble ways of folding and curving the flattened tubular arrangement shown in Fig. 5;

Fig. 11 is a side view of a complete cable of the type shown in Fig. 2, with the coverings broken away for better illustration; and

Fig. 12 is a cross-section enlarged of one of the cable strands.

The problem is therefore to make all strands carry equal currents, or as nearly so as possible or practical. There are several ways of accomplishing this result. Figure 1 is a diagram showing the requirements for complete solution of the problem. The cable is assumed to have eight strands (the small number being assumed to avoid complicating the drawings). Each of the eight strands is shown shifted or transposed so as to occupy successively every strand position in the cross section of the cable, for an equal distance along the cable. Each strand is therefore subjected to the same total inductive effect as every other strand. Each strand therefore carries the same quantity of current.

The transposition can be accomplished in either of several ways, for instance as shown in Figure 4. The practical objection to such a cable would be the large space which it occupies, which would render it very costly to cover the insulation and lead or armor.

In order to eliminate this objection, the cable, after being made up in the circular form shown in Figure 4, could be flattened as shown in Figure 5. In doing this it becomes necessary to introduce a slight insulation between adjacent strands; otherwise, the flat cable would act somewhat like a flat bar of solid copper, in which the greatest current density would be at the outer edges of the bar. The insulation between adjacent strands need be only sufficient to offer a contact resistance between adjacent strands, many times as great as the resistance of one strand for a length of one turn in its progress around the cable, which is in the order of a few thousandths of an ohm. Therefore, a few ohms of insulation resistance between strands will be sufficient for practical purposes. Such extremely light insulation can be obtained in any number of ways, such as by oxidizing the

surface of the metal of the strand or by japanning the surface or by treating the surface chemically in any manner, the main requirement being practically to secure a coating which is extremely thin but which will not rub off in contact with the adjacent strand.

Referring to Figure 5, the flat form of cable is not a convenient or economical form of cable for many purposes, especially in the case of cables requiring an insulating covering overall. To obtain a more convenient shape, the flat cable can be folded or rolled into more compact forms, as shown in Figures 6, 7, 8 and 9, which are diagrammatic, showing only the center line of the strands in one direction in which the strands wind as they advance along the cable.

Since rectangular cables are not usually convenient or economical, the cable can be made into a round form by a rolling process as shown in Figure 10. Cables of substantially round form could be obtained from the original flat form, by folding it into the shapes shown in Figures 8 and 9.

The foregoing forms of cable, while they fulfill the theoretically ideal requirements of complete equalization of currents in all strands still they have practical objections for general use; and by sacrificing an entirely negligible amount of current inequality in the strands a more practical form of cable can be obtained as shown in Figure 3. In this form, the cable is divided into any number of identical segments, each segment consisting of a number of concentric layers or strands. Each strand in any one layer will carry exactly the same quantity of current since each strand is completely transposed and is, therefore, subjected to identically the same inductive effect as every other strand in the same layer. Now to compare strands in different layers, consider the outermost layer; each strand in it alternately occupies a position at the periphery of the round cable and then a position nearest to the center of the round cable. The total induction to which this strand is subjected in the entire length of cable, is, therefore, the same as if the strand were placed throughout its length, in a fixed position at a point very near the center of the segment. The same may be said of every layer in the segment. The current carried by every strand in the segment is the same as if the strand were located at the "center" of the layer. All layers have the same "center" and, therefore, all strands in the segment carry the same amount of current. (It is possible that the geometrical "center" of a layer does not exactly coincide with its inductive "center", but this deviation must be very slight, hence the foregoing statement is correct for all practical purposes).

In view of the foregoing it will be seen that there is very little if anything to be

gained by subdividing the round cable into more than three or four segments. Theoretically two (semi-circular) segments would be sufficient, but practically, three or four segments will be better, depending somewhat upon the total cross section required in the cable. Referring to Figure 3, the four segments shown are laid spirally around each other and, therefore, make the large cable more flexible. There is also another advantageous effect of my construction, viz: the heat generated near the center of the cable cross section is conducted along the strands to the outer part of the cable cross section thereby facilitating the dissipation of the heat from the cable.

Referring to Figure 3, it would be possible to omit the sheets *a* of insulation between the segments without impairing the desired results, provided that the light insulating coating applied to the individual strands is sufficiently durable to withstand rubbing off by contact between adjacent segments.

Figure 2 shows another form of cable, the same as in Figure 3, except that the insulation *a* between segments is continued around the entire periphery of the segment and forms a part of the insulation of the entire cable from ground. A lead sheath *b* and a belt insulation *c* is shown in Figure 2. Obviously, other forms of covering, such as braid or an armor, can be applied, around the cable.

It will be understood, of course, that at the ends of the cable all the strands therein will be electrically connected together to form a single conductor, so that throughout practically the length of the cable the strands composing the same will be in parallel. This is shown in Figure 11, in which *d* designates a copper lug soldered or otherwise electrically connected to all the strand ends. To enable the strand ends to be conveniently prepared for making this electrical connection, I may use as insulation (*e*, Figure 12, which is an enlarged cross section of one of the strands) oxide of copper, which may be readily removed by ordinary soldering flux.

It is to be understood that by power cables I mean those conductors which are adapted to carry alternating current of the usual frequency, namely, 60 cycles per second or less, and it will be further understood that although the insulation may be slight, the resistance must be high i. e., "many times as great as the resistance of one strand for a length of one turn in its progress around the cable", as stated. Also it will be understood that it is important that this resistance shall be of such nature that, as stated, it may be readily removed by ordinary soldering flux or other chemical, this being advantageous in that the chemical may permeate the interior of the large cable, i. e., enter the spaces between the cable strands, thereby avoiding the necessity of spreading apart the ends of the

strands and scraping each strand (which would be an impractical job on a large power cable) whenever it is necessary to solder a lug onto the end of the cable.

5 What is claimed is:

A cable for alternating power currents, composed of a plurality of sectors helically arranged around the axis of said cable, each of said sectors being composed of a plurality of layers of solid wires, each layer being separate and continuous throughout the entire length of the cable, each wire continuing in the same layer throughout the length of the cable and being helically arranged around the axis of its segment, all of said wires and sectors being of the same polarity and connected together electrically at each end of said cable and having sufficient contact-resistance between adjacent wires throughout the length of the cable to tend to prevent current flowing between adjacent wires, for the purposes set forth.

In testimony whereof I hereunto affix my signature.
